UNITED STATES PATENT OFFICE.

ISAAC PATRICK, OF HASTINGS, MICHIGAN, ASSIGNOR TO CONSOLIDATED PRESS COMPANY, OF HASTINGS, MICHIGAN, A CORPORATION OF MICHIGAN.

BLANK-HOLDER TOGGLE-MOVEMENT FOR DRAWING-PRESSES.

1,280,286.

Specification of Letters Patent.

Patented Oct. 1, 1918.

Application filed December 11, 1917. Serial No. 206,640.

To all whom it may concern:

Be it known that I, ISAAC PATRICK, a subject of the King of Great Britain, having taken out my first papers for naturalization 5 as a citizen of the United States, and residing at Hastings, in the county of Barry and State of Michigan, have invented certain new and useful Improvements in Blank-Holder Toggle-Movements for Drawing-Presses; and I hereby declare that the following is a full, clear, and exact description thereof, reference being had to the accompanying drawings, which form part of this 10 specification.

15 This invention is a novel improvement in so-called toggle-drawing-presses and has particular reference to that class of machines in which a blank-holder is employed to hold the work while the same is being operated 20 upon.

The present invention particularly relates to the mechanism for operating the blank-holder, and I will first explain the same with reference to the accompanying drawings, 25 which illustrate one practical embodiment of the invention, and then summarize in the claims the essential features and combination of parts for which I desire protection.

30 In said drawings:

Figure 1 is a conventional side elevation of one type of toggle drawing press, equipped with my novel blank-holder operating devices.

35 Fig. 2 is a front view of Fig. 1.

Fig. 3 is an enlarged diagrammatical sectional elevation of the blank-holder operating means, showing the positions of the parts near the ends of the downward strokes of 40 the blank-holder and plunger.

Fig. 4 is a similar view showing the position of said parts during the upward movement of the blank-holder and plunger; the blank-holder being almost fully raised, and 45 the plunger raised about half way.

Fig. 5 is an enlarged vertical sectional view on the line 5—5, Fig. 1.

The machine indicated in Figs. 1 and 2 is a so-called double-acting toggle-drawing 50 press; the particular construction of such press is not an essential of the present invention. The machine indicated is usually provided with a main plunger B which is connected by a pitman b to a crank t, on a main crank shaft T, which main shaft may

be operated in the usual manner by suitable gearing which it is not necessary to show or describe in detail.

A blank-holder A, of a well known type, is shown surrounding the plunger B and suspended by adjustable bolts D from yokes C, which yokes are connected, at the opposite sides of the machine, by pairs of links E, E' to arms F, F' on rock shafts S, S', which shafts are journaled in suitable bearings on the sides of the main frame of the press and near the top thereof in the usual manner.

At one side of the machine the shafts S and S' are provided with crank arms G, G', 70 to which arms are connected toggle links H, H' that in turn are pivotally connected together at O; this pivot O being attached to a lever J, which is pivotally connected at one end to a crank K on the adjacent end 75 of the main shaft T, crank K being so disposed relatively to the crank t that the blank-holder will be actuated at the proper time and in the desired relation to the movement of the plunger B.

The lever J extends beyond the pivotal connection O of the links H, H' thereto and its free end, opposite its connection to the crank k, is engaged with a guiding cam member N. This cam member is preferably 80 a fixed race cam, and it is engaged by a roller M on the end of lever J as indicated in the drawings. The roller M is securely fastened to the free end of lever J but is free to move around the cam member N.

As the shaft is rotated the lever J will be oscillated by the crank and the roller M will traverse the race way in cam member N and so guide the upper end of the lever J as to keep the pivot O in the desired 90 relation to the shafts S, S', at all times.

Operation.

The main shaft T is operated by suitable gearing in the usual manner so as to reciprocate the plunger B. As the shaft T revolves the lever J, being attached at one end to crank K, moves with said crank, but the movement of the upper or free end of said lever is controlled by the engagement of 100 roller M with the cam N. This cam is so shaped that the path traversed by the roller M has such relation to the path of the pivot connecting lever J to crank K that the fulcrum point O, or connection between the 110

links H and H', will travel in an approximately vertical line, or perpendicular to the shaft T and intermediate the shafts S, S'.

Cam member N insures that proper and desired uniform and equal rocking movements will be imparted from the crank K through lever J and links H, H' to the shafts S, S'. The roller M prevents any deflection of the pivot or fulcrum point O from the desired line of movement which it should traverse during the operation of the blank-holder, and insures a straight line of travel of the pivot O.

By this means the blank-holder is raised and lowered in correct relation to the plunger B, so that the blank-holder will be lowered to engage and hold the work just before the plunger begins to operate thereupon; will hold the work while the plunger begins to withdraw therefrom; and will then raise and release the work.

In the example shown the blank-holder dwells during a period of not less than 90 degrees while crank K is passing over the top center of the cam member, and the toggle formed by the blank-holder connections will dwell on the drawing stroke until the crank shaft T has passed through an arc of 90 degrees.

30 What I claim is:

1. In a drawing press having a plunger, a crank shaft and connections for operating the plunger, a blank-holder; a pair of rock-shafts and operative connections between the rock-shaft and the blank-holder; a crank, a lever connected with said crank, a cam engaging the lever for guiding same, and links connecting the lever with arms on the rock-shafts.

40 2. In a drawing press having a main shaft a plunger, means for operating the plunger from the main shaft, a blank-holder, a pair of rock-shafts and links connecting arms on said shafts with the blank-holder; a crank on the main shaft, a lever connected with this crank, a cam controlling the movement of the free end of the lever, and links connecting this lever with arms on the rock-shaft.

50 3. In a drawing press having a crank shaft, a plunger and connections for operating the plunger from the crank shaft, a pair of rock-shafts, and links connecting arms on the rock-shaft with the blank-holder; a crank on the main shaft, a lever connected with said crank, a fixed cam engaging the free end of the lever for guiding same, and links connecting arms on the rock-shaft with said lever.

60 4. In a toggle drawing press the combination of a main plunger and means for operating same, and a blank-holder, with a

crank, a fixed cam, a lever having one end pivotally connected with the crank and the other end movably engaged with said crank; 65 rock-shafts at opposite sides of the lever, links pivotally connected with said lever intermediate the crank and free end of the lever, arms on the rock-shaft connected with said links, and operative connections between the rock-shaft and the blank-holder.

5. In combination a blank-holder, a pair of rock-shafts, arms on the rock-shafts, links connecting the arms with the blank-holder, a rotating crank, a fixed cam member, a lever 75 pivotally connected to said crank at one end and having its other end movably engaged with said cam member, links connected with said lever intermediate the crank and the cam, and arms on said rock-shaft connected 80 with said links.

6. In a toggle drawing press the combination of a main plunger, a main shaft, and means for operating the plunger from said shaft, a blank-holder, a pair of rock-shafts, 85 arms on the rock-shafts, links connecting such arms with the blank-holder; a crank on the main shaft, a fixed cam member, a lever pivotally connected to said crank at one end and having its other end movably 90 engaged with said cam member and links connected with said lever intermediate the crank and the cam and with arms on said rock-shaft, substantially as described.

7. In a drawing press having a main 95 plunger, means for operating the plunger, and a blank-holder; rock-shafts; arms on said rock-shafts; links connecting arms on the rock-shafts with the blank-holder; a rotatable crank; a lever connected with this 100 crank and oscillated thereby; a cam controlling the movement of the lever; and links connected with this lever at a point intermediate its ends and with arms on the rock-shafts, said cam causing the point of 105 connection of the link with the lever to move in a straight line as the crank rotates.

8. In a toggle drawing press the combination of a main plunger; means for operating same; a blank-holder; a rotatable 110 crank; a fixed cam; a lever having one end pivotally connected with the crank and its other end movably engaged with said cam; blank-holder operating means; and connections between a point on said lever intermediate the ends thereof and the blank-holder operating means, said cam causing the point of connection of the link with the lever to move in a straight line as the crank rotates.

120 In testimony that I claim the foregoing as my own, I affix my signature.

ISAAC PATRICK.
